UNITED STATES PATENT OFFICE.

CHRISTIAN F. BREMER, OF TAMPA, FLORIDA.

CIGAR-MAKING MACHINE.

1,182,891.

Specification of Letters Patent. Patented May 16, 1916.

Application filed November 2, 1914. Serial No. 869,898.

To all whom it may concern:

Be it known that I, CHRISTIAN F. BREMER, a citizen of the United States, residing at Tampa, in the county of Hillsboro, State of Florida, have invented certain new and useful Improvements in Cigar-Making Machines; and I do hereby declare the following to be a full, clear, and exact description of the invention, such as will enable others skilled in the art to which it appertains to make and use the same.

This invention relates to cigar making machines and particularly to bunch shaping, compressing and conveying mechanism therefor.

The object of the invention resides in the provision of a cigar making machine of the type named which can be operated by a single person in a simple manner and which can be transferred from one location to another with facility.

A further object of the invention resides in the provision of a cigar making machine embodying an improved construction of endless molds and which can be operated either by hand or foot power.

With the above and other objects in view the invention consists in the details of construction and in the arrangement and combination of parts to be hereinafter more fully described and particularly pointed out in the appended claims: it being understood that various changes in the form, operation, size, and minor details of construction within the scope of the claims may be resorted to without departing from the spirit or sacrificing any of the advantages of the invention.

In describing the invention in detail reference will be had to the accompanying drawings wherein like characters of reference denote corresponding parts in the several views, and wherein—

Figure 1 is a plan view of the invention; Fig. 2, a side view of same; Fig. 3, a section on the line 3—3 of Fig. 2; Fig. 4, an end view of the machine; Fig. 5, a section on the line 5—5 of Fig. 2; Fig. 6, a section on the line 6—6 of Fig. 2; Fig. 7, a longitudinal section of the machine; Fig. 8, a detailed perspective view of abutting sections; and Fig. 9, a detailed perspective view disclosing the hinge connection between adjacent blocks of the conveyer.

Referring to the drawing the invention is shown as comprising a frame A which is adapted to be detachably secured to a sup-

porting part. The frame A includes side members 11 and 12. Mounted in the side member 11 at each end thereof is an adjustable bearing 13, while corresponding adjustable bearing 14 is in the side member 12. The bearings 13 and 14 are adjustable longitudinally of the machine, and rotatably mounted in the bearings 13 and 14 at one end of the machine is a shaft 15, while another shaft 16 is rotatably mounted in the bearings 13 and 14 at the other end of the machine. Fixed on the shaft 15 are spaced square blocks 17, while corresponding blocks 18 are fixed on the shaft 16. Rotatably mounted in the side members 11 and 12 is a transverse shaft 19 which has fixed thereon a gear 20 meshing with a gear 21 fixed on the shaft 15. Also fixed on the shaft 19 is an operating crank 22 whereby said shaft may be manually rotated. Fixed on opposite ends of the shaft 19 respectively are pulleys 23 for the purpose of connecting the shaft with a foot pedal (not shown) to enable the shaft to be rotated by means of foot power. Travelling about the shafts 15 and 16 is an endless conveyer B formed of a plurality of blocks 24. Adjacent blocks 24 are hingedly connected together at their inner edges as at 25 and the inner faces of these blocks 24 are provided with spaced recesses 26 adapted to receive the blocks 17 and 18 during travel of the conveyer B. Each block 24 has formed on its outer face a dovetail rib 27 for a purpose that will presently appear. Each rib 27 is provided at one end with a nib or stop 28 and further provided with a longitudinal groove 29 opening through the opposite end thereof. Mounted in each groove 29 is a spring latch 30 for a purpose that will presently appear.

Secured to each block 24 is a mold section 31, said mold section being provided with a longitudinal dovetail groove 32 in one face thereof whereby it is detachably engaged with the desired block 24, the groove 32 of the mold section receiving the rib 27 of the block. The movement of the mold section on respective blocks 24 is limited by engagement of one end of the section with a stop 28. When a mold section has been fully applied to a given block 24 the latch 30 will automatically engage the end of the section remote from the stop 28 and thereby lock the section against disengagement from the block. Formed in one of the abutting faces of each section 31 is a longitudinally dis-

posed recess 33 which corresponds in size and shape to the size and shape of the cigar to be formed. Projecting from the opposing face of the next adjacent section 31 is 5 a complementary projection 34 which is adapted when the sections are disposed in abutting relation to partially extend into the recess 33 and thereby compress the tobacco.

10 In order to prevent the sections 31 and the blocks 24 from buckling during travel and also to force adjacent sections 31 firmly together there are mounted in the side member 11 vertically slideable bearings 35 each 15 of which is forced downwardly by means of springs 36 respectively. Likewise there are mounted in the side member 12 vertically slideable bearings 37 corresponding to the bearings 35 and normally pressed downwardly by means of springs 38 respectively. Journalized in aligned bearings 35 and 37 are rollers 39 which engage the outer faces of the sections 31 during the operation of the conveyer. Also mounted between the side 20 members 11 and 12 are spring-pressed rollers 40 and 41 which engage the lower portion 25 of the conveyer B, the tendency of said rollers being upward.

In the operation of the machine the workman at one end deposits the filler in one of the mold sections 31 and then rotates the shaft 19 through the medium of the crank 22 to bring the next mold section in position to receive the filler. This operation is continued as long as desired. As the mold sections reach the end of the machine remote from the workman supplying the filler, said section will open as will be obvious when the compressed filler is removed by the 40 workman who is to roll the cigar.

What is claimed is:—

1. In a machine of the class described, the combination of a pair of spaced shafts, a conveyer trained around said shafts, said

conveyer comprising a series of hingedly connected blocks, mold sections detachably interlocking with said blocks respectively, and means for operating the conveyer.

2. In a machine of the class described, the combination of a pair of spaced shafts, a plurality of spaced bearings fixed on said shafts respectively, a conveyer trained around said shafts, said conveyer comprising a series of hingedly connected blocks, each of which is provided on its inner face with a plurality of recesses adapted to respectively receive the bearings on said shafts during the travel of the conveyer, mold sections detachably interlocking with said blocks respectively, and means for operating the conveyer.

3. In a machine of the class described, the combination of a pair of spaced shafts, a conveyer trained around said shafts, said conveyer comprising a series of hingedly connected blocks, dovetail ribs on the outer faces of said blocks, mold sections having dovetail grooves on their inner faces detachably receiving said ribs, and means for operating the conveyer.

4. In a machine of the class described, the combination of a pair of spaced shafts, a conveyer trained around said shafts, said conveyer comprising a series of hingedly connected blocks, dovetail ribs on the outer faces of said blocks, mold sections having dovetail grooves on their inner faces detachably receiving said ribs, means for locking the mold sections against longitudinal movement on said blocks, and means for operating the conveyer.

In testimony whereof I affix my signature, in the presence of two witnesses.

CHRISTIAN F. BREMER.
